[57] CLAIM

The ornamental design for a clothes hamper liner, as shown and described.

DESCRIPTION

FIG. 1 is a perspective view of a clothes hamper liner showing my new design with one of the separable pockets being partially removed;

FIG. 2 is a reduced side elevational view thereof shown with pockets in place inside the liner, the opposite side being a mirror image;

FIG. 3 is a front elevational view thereof, the rear being a mirror image;

FIG. 4 is a top plan view thereof; and,

FIG. 5 is a bottom view thereof.

FIG. 1

FIG. 2

FIG. 3

FIG. 4

FIG. 5
